STACY B. HASELTINE, OF CHICAGO, ILLINOIS, ASSIGNOR TO WILLIAM H. MINER, OF CHICAGO, ILLINOIS.

DRAFT-RIGGING.

1,160,603.

Specification of Letters Patent. Patented Nov. 16, 1915.

Application filed June 12, 1911. Serial No. 632,695.

To all whom it may concern:

Be it known that I, STACY B. HASELTINE, a citizen of the United States, residing in Chicago, in the county of Cook and State of Illinois, have invented a new and useful Improvement in Draft-Rigging, of which the following is a specification.

This invention relates to an improvement in means for connecting the ordinary coupler with the ordinary draft rigging employed in railway cars.

The invention consists in providing a connecting head adapted to receive the end of the coupler and be secured thereto by means of the usual flat key, with means for receiving and holding a detachable U-shaped band or yoke of metal inclosing the friction or other regulating draft device. And the invention further consists in the novel parts, devices and combinations of parts and devices hereinafter claimed.

In the accompanying drawing which forms a part of this specification, Figure 1 is a side elevation, partly in section, and Fig. 2 is a plan view of the coupler and the means for uniting the same with the draft rigging. Fig. 3 is a section on line 3—3 of Fig. 1. Fig. 4 is an enlarged detail view of the gib or hook on the end of the yoke. Fig. 5 is an enlarged view of a part of Fig. 2.

In said drawing, A represents an ordinary coupler and B the key for securing the same to the draft yoke.

C is the head of the draft yoke, secured to the coupler by the said key B.

D represents any ordinary shock absorber or draft regulating device, such as is commonly employed in conjunction with car couplers. E is the front follower of said draft device and F the rear follower thereof.

K, K are the side draft castings carrying the follower stops against which the followers E and F bear to and fro in the action of the draft rigging.

G is a metallic band or yoke, preferably made of wrought iron, U shaped and having at its two free ends a turn or gib H to engage in curvilinear slots formed in the head C, the walls of which slots form stops J, J,

J¹ J¹. The gibs are bent outward from each other and should preferably be bent in rounded form, as indicated in Fig. 5, to avoid putting strains in the metal and to preserve the strength thereof. The head C 55 is made in the form of a continuous band to surround the coupler, and leave at the upper sides thereof room for the snug insertion of the yoke G.

The parts are assembled by inserting the 60 yoke G, carrying the draft regulating devices in the head or band C, the gib H entering between the stops J and the counterstops J¹ of the said head. The coupler is then placed in the head and locked 65 thereto by the key B which passes laterally through the head, the coupler and the car sills L L. This means for connecting the coupler with the draft regulating devices is applicable to any ordinary coupler and 70 any of the ordinary well known friction or other shock absorbing draft gears, is cheap, durable and relatively light for its strength.

I prefer to make the U-shaped yoke of wrought iron on account of its superior 75 strength and flexibility, and also incidentally because it is cheaper than cast steel. The form is one which lends itself readily to being forged into shape without loss of strength, and when finished may be readily 80 inserted in the head C by flexing the two free ends to pass them within said head, permitting them to spring out into engagement when in place, though it will be understood that the resiliency of the band is not 85 at all relied upon to maintain the engagement of its ends or gib with the head; because when the coupler is inserted within and keyed to the head, it entirely fills the space so that there can be no subsequent 90 escape of the yoke from its engagement with the head, as will be understood by reference to Figs. 3 and 4.

The purpose of the curved slots formed in the head C is so that there may be a lateral 95 freedom of movement between the coupler and the yoke. And to permit this, it will be noticed in Fig. 5 that a lateral clearance at each side is allowed between the head and the sides of the gibs. This permits the 100

coupler to move laterally to a certain extent without putting strain upon the shock absorbing draft devices or causing them to bind in their operation. One of the special advantages of this method of connecting the coupler with the shock absorbing draft devices is the ease of applying and removing the coupler while the car is in service, to do which, all that is required is to remove the key B, whereupon the coupler may be withdrawn bodily from the head C and from the car; and may be applied to the car by simply reversing this operation and without the necessity of distributing the draft rigging or other parts.

Although I have herein used the terms "head" and "yoke" to describe the members C and G, respectively, various other terms may be employed to aptly describe the same. For instance, those skilled in the art may call the member C a "hood", or "coupler pocket"; and the yoke G may be designated as a "loop", "U-shaped strap", or "yoke strap".

25 I claim:—

1. The combination with shock absorbing draft devices, of a U-shaped yoke having integral attaching means at its two free ends, a head to which said free ends are attachable, a coupler to which said head is keyed, and a key uniting said head and coupler, said yoke being readily detachable from the head when the key and coupler are removed, substantially as specified.

30 2. The combination of the coupler, the band-like head surrounding the same and provided with stops and counterstops, of the shock absorbing draft devices, the U shaped band or yoke surrounding said shock absorbing draft devices and having at its free ends the gibs for engaging the stops and counterstops in said head, the free ends of said yoke being passed within the head between it and the coupler when assembled, substantially as specified.

35 3. In combination, a U-shaped yoke having outwardly turned, curvilinear gibs formed on the free ends of the arms thereof, a coupler, and means for connecting the coupler and yoke, said means including a head having curvilinear slots in which are adapted to take the curvilinear gibs formed on the ends of the arms of the yoke, the walls of said curvilinear slots forming stops for said gibs, and said slots and gibs being so formed as to allow the coupler to swing laterally relatively to the yoke.

40 4. In combination, a U-shaped yoke having gibs formed on the free ends of the arms thereof, a coupler, a rectangular head having slots therein within which said gibs are adapted to take, and means for detachably securing said coupler and head together, the arms of the yoke being detach-

able from the head only when the coupler is removed from the latter, substantially as specified.

5. In a draft rigging for cars, the combination with the yoke, of a draw bar hood swingingly mounted on the forward end of said yoke.

6. In a draft rigging for cars, the combination with the yoke, of a draw bar hood swingingly mounted on and constructed to receive the forward end of the yoke, the diameter of the hood being greater than the width of the yoke, whereby the hood may swing, and the yoke act as an abutment to limit the swinging movement of the hood.

7. In a draft rigging for cars, the combination with the draft sills having elongated key ways therethrough, a draft gear mounted between said sills, having front and rear followers, a bearing on the upper and lower side of the yoke of the gear, a hood pivotally mounted on said bearings and provided with elongated key slots, a draw bar the rear end of which is mounted in said hood and a key passing through the slots in the draft sills, hood and a slot in the rear end of the draw bar whereby the draw bar is locked to said hood and is free to swing with the hood.

8. In a device of the character described, a yoke strap and means adapted to connect said strap to a draw-bar, said means consisting of a hollow head surrounding the yoke and adapted to be connected to the draw-bar and held in position on the yoke by means formed integral with the yoke.

9. In a device of the character described, a yoke strap and means for connecting said strap to a draw-bar, said means consisting of a hollow head surrounding the yoke and connected to the draw-bar and separable from the yoke without destructive effort.

45 10. In combination a draw-bar and a yoke, the latter consisting of a jaw member and a loop, the jaw member having a longitudinal opening to admit the draw-bar and loop and being provided with sockets, the loop having studs to fit the sockets, and means in the form of a horizontal key for connecting the jaw member and draw-bar being slotted to receive the key.

11. A yoke for draft gears consisting of a jaw member and a vertical loop, the jaw member having top and bottom sockets and the loop having a stud at the forward end of each arm to engage the sockets.

12. In a device of the class described, a yoke strap and a draw bar, a hollow head uniting the same and means penetrating the hollow head only and adapted to locate the yoke strap and hollow head in operation.

13. The combination with the shank of a car coupler, of a yoke comprising a socket

in which said coupler shank is detachably secured, and a strap the ends of which straddle said coupler shank in said socket and have outwardly projecting pivot bosses entering holes in the adjacent walls of the socket, substantially as set forth.

14. In a device of the character described, the combination of a yoke strap, a hollow head and a draw-bar, the head being movable relative to the yoke strap when in operative position.

15. In a device of the class described, a draw-bar and a yoke strap, a hollow head embracing said draw-bar and strap and provided with an extended fork, and means penetrating said fork and adapted to unite the parts of the device together.

16. In a device of the character described, a yoke strap and means for connecting said strap to a draw-bar, said means consisting of a hollow head surrounding the yoke and connected to the draw-bar by a key passing through the hollow head and draw-bar, said head being held in position on the yoke by means formed integral with the latter.

17. In a device of the character described, the combination with a vertical yoke strap, of a hollow head, a draw-bar, and a key, said head being movable relatively to the yoke strap when in operative position.

18. In a device of the character described, the combination with a vertical yoke strap, of a hollow head, a draw-bar, and a key extending through openings in said head, the head being movable relatively to the yoke strap when in operative position.

19. In a device of the character described, the combination with a vertical yoke strap of a hollow head, a draw-bar and a key extending through the draw-bar and the sides of the hollow head, said head being movable relatively to the yoke strap when in operative position.

20. A yoke for railway draft gears which consists of an attaching member and a loop having two free arms the ends of which are independently detachably and pivotally connected with said attaching member.

21. In combination, a draw-bar and a yoke for draft gears, the yoke consisting of an attaching member and a loop having two free arms the ends of which are independently pivotally connected with said attaching member, said attaching member having a longitudinally extending opening to receive said draw-bar and to admit said loop, the latter protruding from the attaching member at the rear of the latter, said attaching member and draw-bar being slotted to receive a coupler key.

22. A draft yoke which consists of a hollow attaching member and a loop within said attaching member, said loop having two free arms the ends of which are pivoted at

their forward ends to said attaching member, 65 said loop extending to the rear through the attaching member and protruding therefrom for a greater portion of its length, said attaching member being provided with horizontally extending slots adapted to receive 70 a coupler key.

23. In a device of the character described, a yoke strap having two free ends and means for connecting said strap to a draw-bar, said means consisting of a hollow head surrounding 75 said ends of the yoke and transversely slotted for the passage of a coupler key, said yoke strap and head being separable without destructive effort.

24. In a draft rigging the combination 80 with a draw-bar and yoke having two free arms, of a coupler pocket detachably connected to the rear end of said draw-bar and detachably interlocked separately with the arms of said yoke.

25. The combination with a draw-bar and yoke having two free arms, of a coupler pocket detachably connected to the rear end of said draw-bar, said coupler pocket being pivotally connected separately to the arms 90 of said yoke.

26. A draft yoke for draft riggings comprising an intermediate connecting member adapted to be detachably secured to the shank of a coupler, and a strap portion having two free arms the ends of which are pivotally connected with said connecting member.

27. A yoke for draft riggings comprising a cast metal part adapted to be detachably 100 secured to the shank of a coupler, and a strap of wrought metal having two free arms the ends of which are pivotally connected with said cast metal part.

28. In a device of the character described, 105 a yoke strap, and means for connecting said strap to a draw-bar, said means consisting of a hollow head adapted to be detachably connected to a draw-bar, said head being attached to the yoke strap by means different 110 from those by which the head is adapted to be attached to the draw-bar.

29. In a device of the character described, a vertical yoke strap and means for connecting said strap to a draw-bar, said means 115 consisting of a hollow head adapted to be connected to a draw-bar, said head being provided with recessed portions to receive the ends of the yoke strap.

30. In a device of the character described, 120 a vertical yoke strap and means for connecting said strap to a draw-bar, said means including a hollow head to which the yoke strap is attached, said head being transversely slotted for the passage of a coupler 125 key.

31. As an article of manufacture, a hollow yoke head provided with transverse slots to

receive a coupler key, said head having upper and lower recesses to receive the ends of a yoke strap.

32. A yoke for railway draft riggings which consists of a wrought iron U shaped strap portion and a cast metal hollow head within which is adapted to be received the butt end of a draw-bar, the ends of the arm of the strap being attached to the cast head

and the cast head being adapted to be detachably connected with a draw-bar by means different from those by which the head is adapted to be attached to the draw-bar.
